United States Patent Office.

SAMUEL HILLIER, OF ALLEGHENY, PENNSYLVANIA.

Design No. 3,762, dated November 23, 1869.

DESIGN FOR A COFFIN.

The Schedule referred to in these Letters Patent and making part of the same.

I, SAMUEL HILLIER, of the city and county of Allegheny, and State of Pennsylvania, have invented and produced a new and original Design for Coffins, of which the following is a specification.

The nature of my design is fully represented in the accompanying photographic illustration, to which reference is made.

I claim, as my invention, the design for a coffin, as shown.

SAMUEL HILLIER.
